UNITED STATES PATENT OFFICE.

ERNST G. LANCE, OF DETROIT, MICHIGAN, ASSIGNOR OF ONE-HALF TO OTTO C. RUSS,
OF LAKE ODESSA, MICHIGAN.

WINDOW LOCK.

Application filed May 13, 1921. Serial No. 469,081.

To all whom it may concern:

Be it known that I, ERNST G. LANCE, a citizen of the United States of America, residing at Detroit, in the county of Wayne and State of Michigan, have invented certain new and useful Improvements in Window Locks; and I do hereby declare the following to be a full, clear, and exact description of the invention, such as will enable others skilled in the art to which it appertains to make and use the same.

This invention relates to a lock for windows. It is a primary object and purpose of the present invention to make a lock adapted for application to windows of the sliding type, whereby the sashes of the window may be locked together against movement in one direction, so as to insure against the window being opened any farther than it has been opened, and also lock the sashes in either open or closed position, the locking or unlocking of the sashes and of the same to or from the window casing being simultaneous and operable through manual actuation of a single operating means. A further object of the invention is to provide a window lock of this character which is very simple in its structure, making it easy to manufacture at low cost, and which is particularly easy to install, no tools other than a screw driver being required. Many other objects and purposes than those stated will appear fully and in detail, together with the novel constructions and arrangements of parts for attaining the same, as understanding of the invention is had from the following description, taken in connection with the accompanying drawing, in which,

Fig. 1 is a fragmentary perspective view showing my invention of window lock applied to a window.

Fig. 2 is a horizontal section through the locking member which is applied to the lower sash of the window, the operating mechanism appearing in plan view.

Fig. 3 is a vertical section taken substantially on the broken line 3—3, of Fig. 2, and

Fig. 4 is a view similar to that shown in Fig. 2, showing the operating mechanism in a different position.

Like reference characters refer to like parts in the different figures of the drawing.

The invention is adapted for application to windows having sliding sashes mounted for vertical movements in a window casing.

The upper sash 1, lower sash 2 and casing 3 are of usual and conventional construction. In the application of my invention, on one vertical side 4 of the upper window sash a bar 5 of metal is secured, having ends 6 which are bent inwardly to provide feet which are attached to the side 4 by screws, the main body of the bar between said feet being spaced a short distance from the front side of the side 4 of the sash. At regularly spaced apart intervals in the length of the bar 5 the metal is cut at three sides and pressed inwardly at an angle, as indicated at 7, making in effect a ratchet with spaced apart teeth.

On the window casing 3 a second bar 8 of flat metal is located, it having end portions 9 and an intermediate portion 10 set inwardly through which screws pass to attach the bar to the casing, the other main portions of the bar being set outward from the casing a short distance as shown. In the length of the bar 8, a plurality of openings 11 are made spaced at regular intervals equal to the spacing apart of the ratchet depressions in the bar 5 attached to the upper window sash.

On the upper frame member 2^a of the lower sash 2, the lock is attached. In structure, this lock includes a base plate 12 which is adapted to lie against the upper side of member 2^a, and which at one end is formed into a sleeve 13 from which a section 14 depends, adapted to lie against the inner side of the member 2^a. Screws are passed through the plate 12 and the depending section 14 to attach the lock to the member 2^a. A locking pin 15 is slidably mounted in the sleeve 13 and at one end is adapted to enter any of the openings 11 in the bar 8.

Plate 12 at the end thereof nearest the upper sash has a narrow extension from each side edge of which an ear 16 is turned upwardly, and a locking dog 17 is pivotally mounted on and between said ears, its upper end being formed so as to engage with any of the ratchet depressions in bar 5 formed by the inwardly pressed parts 7. The dog 17 is normally spring pressed toward the bar 5 so as to engage with the same by a leaf spring 18 which is securely attached to the under side of the top of a covering housing 19 lying over the plate 12 and attached thereto by the pin 20, it being evident that the sides of this housing may have project-

ing tangs to pass through openings in plate 12 to position the same on the base plate.

A lever 21 is pivotally mounted between its ends at 22 on the base 12, one end thereof being turned upwardly at 23 so as to come directly back of the lower end of the locking dog 17. The opposite end is divided and forked, as indicated at 24, and a pin 25 attached to the pin 15 and extending upwardly therefrom through a curved slot 26 in the upper side of the sleeve 13 passes between the two parts of the forked end, as shown. An operating arm 27 is turned upwardly from one side of the lever 21 and extends upwardly through a slot 28 in the upper side of the housing 19 whereby the lever 21 may be turned to different positions by hand.

With the lever 21 in the position shown in Fig. 4, the locking pin 15 is drawn into the sleeve 13 and the lower end of the locking dog 17 is engaged by the upturned lip 23 to thereby move the upper end of the dog away from the ratchet bar 5, the sashes of the window both being free for sliding movement. When the lever is moved to its other position as shown in Fig. 2, the locking pin 15 is projected outwardly so that it may enter an opening 11 in bar 8, and which opening it shall be is a matter of choice with the operator, it being evident that the lower sash may be locked in closed position or at a number of positions in which the lower sash is more or less raised or elevated above its lower position. At the same time, the lip 23 is moved away from the dog 17 whereupon it is pressed by spring 18 so as to bear at its upper end against the bar 7 and enter any ratchet depression therein to which said upper end comes. The operation of the locking pin 15 to locking position and the freeing of the dog 17 so that it may serve its locking function are simultaneous and it is likewise evident that both sashes of the window are simultaneously freed for movement at one and the same time. The operation of the lever 21 controlling both locking members is through manual actuation of the operating member 27 where it extends above the top of the housing 19.

The construction is relatively simple, is easily manufactured from sheet metal, has no parts to break or otherwise get out of order, and with it either or both of the window sashes may be locked either in closed position or in a number of partly open positions from which neither can be moved to open them wider, though the upper sash may be moved upwardly if it is partly lowered. This precludes the unauthorized entrance from the outside of anyone, as the window cannot, under any circumstances, be opened more widely. Of course the bars 5 and 8 may be longer if desired and a larger number of positions for the window sashes

provided, this being a matter of design. 65 Various other changes in detail of construction may be made without departing from the invention defined in the appended claims, and I consider myself entitled to all forms of structure coming within the scope of the 70 appended claims defining the invention.

I claim:

1. A lock for windows, comprising a base plate formed at one end with a sleeve and at its other end with a pair of upturned ears, 75 a dog pivotally mounted between said ears, a housing positioned over and secured to the base plate, a spring on the housing acting on the dog, a locking pin slidably mounted in the sleeve, a pin attached to the locking pin 80 and extending upwardly through a slot in the sleeve, a lever pivotally mounted on the upper side of the base and formed at one end with a fork to receive the last mentioned pin and at its opposite end with an upturned lip 85 adapted to come directly against the lower end of the dog in one position of the lever, and an operating handle extending upwardly from the lever through a slot in the housing.

2. A lock for windows, comprising a base 90 plate formed at one end with a sleeve, a dog pivotally mounted at the opposite end of the plate to turn on a horizontal axis and extending above the plate, a housing located over and connected to the base plate, a spring secured to the housing and acting on the dog to force its upper end outwardly, a locking pin slidably mounted in the sleeve, a lever pivotally mounted on the upper side of the base, means at one end of the lever having 100 connection with the pin for moving the pin longitudinally on pivotal movement of the lever, means at the opposite end of the lever to act on the dog on pivotal movement of the lever and move its upper end inwardly 105 against the force of the spring, and an operating handle extending upwardly from the lever through a slot in said housing, substantially as described.

3. A lock for windows, comprising a base 110 plate having a transverse sleeve formed at one end, a pin slidably mounted in said sleeve, a lever pivotally mounted between its ends on the plate, interengaging means between one end of the lever and the pin, said other end of the lever having a portion off-set from the longitudinal center line of the lever and terminating in an upturned ear, a dog pivotally mounted to turn on a horizontal axis at the opposite end of the plate against the lower end of which said ear bears, spring means normally turning the upper end of the dog outwardly, and means for manually turning the lever about its pivot, substantially as described. 115 120 125

In testimony whereof I affix my signature.

ERNST G. LANCE.
